Patented Aug. 13, 1929.

UNITED STATES PATENT OFFICE.

GEORGE B. SMALL, OF TULSA, OKLAHOMA, ASSIGNOR OF THREE-FOURTHS TO TIDAL
OIL COMPANY, OF TULSA, OKLAHOMA, A CORPORATION OF OKLAHOMA.

PNEUMATIC PUMPING APPARATUS.

Application filed December 24, 1927. Serial No. 242,505.

My invention relates to pneumatic pumping apparatus, and more particularly to apparatus for supply of air or gas to a well for displacing fluid therefrom, the principal object of the present invention being to control the displacing flow of air or gas in response to pressure induced by rising head of fluid in the well; the present invention being an improvement on that forming the subject matter of my co-pending application Serial No. 229,414.

In accomplishing this and other objects of the invention I have provided improved details of structure, the preferred forms of which are illustrated in the accompanying drawings, wherein:

Fig. 1 is a side elevation of the apparatus, illustrating parts of the valve mechanism and well in central vertical section, the parts appearing as when the displacing flow is interrupted to permit accumulation of oil in the well.

Fig. 2 is a similar view, illustrating the parts as they appear when admitting flow for displacing oil from the well.

Referring more in detail to the drawings: 1 designates a well hole terminating in the usual shot hole 2 and 3 a well casing comprising a shoe 4 seated on cap rock 5 above the oil sand 6, in accordance with common practice.

The casing 3 is capped by a head 7 to seal the casing and retain the artificial fluid pressure medium therein.

Extending through the head 7 is tubing 8, preferably equipped at its lower end with a liquid trap 9, comprising a cylindrical body 10 of larger diameter than the tubing, a reduced neck 11 at its upper end threaded onto the tubing, and a closed bottom 12 having a built-up boss 13, provided with a port 14.

Threaded into the port 14 and depending into the well pocket is a strainer pipe 15, and threaded into the port 14 and extending into the trap chamber 16 is a nipple 17 carrying a downwardly seating check valve 18, through which oil admitted to the strainer pipe is passed to the trap chamber, but prevented from return to thereby effect collection of a charge in the trap.

A fitting 19 on the tubing above the casing head provides connection for a flow line 20 through which displaced oil is delivered to a pipe line, or storage, and extending through a reducing coupling 21 on the T fitting and

through the tubing into trap 9 is a conduit 22 for conducting a major flow of artificial pressure medium, hereafter referred to as air, into the trap for release within oil accumulated in the trap.

The conduit 22 is of sufficiently less diameter than the tubing 8 to provide an annular channel 23 between the conduit and tubing through which oil displaced from the trap is delivered into the flow line 20, and leading through the casing head and to near the bottom of the casing, exteriorly of the tubing 8, is a conduit 24 for conducting the pressure created therein by the rising head of the oil to the mechanism for controlling flow of air to the well which will hereafter be described.

Mechanism for controlling flow of air to the well through line 22 comprises a valve housing 25 having an upper cover plate 26 and a lower cover plate 27 secured to the housing by bolts 28; secondary valve units 29 and 30, including valve and diaphragm housings 31 and 32, being mounted on the upper plate 26 as and for the purpose presently described.

The assembled housings 25, 31 and 32 are supported by a chair 33 from a suitable base, here shown to consist of a pressure tank 34, forming part of the apparatus, and to which the chair is attached by bolts 35, extended through feet 36 on the chair legs 37.

The master valve chest 25 includes spaced chambers 38 and 39, having inwardly facing seats 40 and 41, connected by a throat 42, and contained within the respective chambers is a valve 43 and a piston 44 of differential areas, rigidly connected by a stem 45, having a reduced shank 46 at one end extended through the valve 43 and forming a shoulder 47 to which the valve is held by a nut 48; the other end of the stem extending through the piston 44 and having a shoulder 49 to which the piston is held by a nut 50.

A channel 51 opening laterally through the stem and extending through the upper part thereof, provides open communication between the throat 42 and the part of the chamber 39 above the piston 44, the end of the channel opening into the upper portion of the chamber 39 being restricted as at 52, for a purpose presently described.

The piston 44 has a valve head 44' on its lower end adapted to seat on the seat 41, and

having a lower face of smaller area than the top of the piston to provide a preponderance of pressure on the piston for holding the head 44' on its seat when pressure is balanced in the chamber 39 and throat 42.

Opening laterally from the throat 42 is a port 53, and threaded into said port is a nipple 54 having a reducing coupling 55 for the conduit 22, through which the major flow of air is delivered to the well; the conduit 22 being equipped with a hand valve 56 for manually controlling the flow.

Opening through the cover plate 27 at the lower end of the valve chest is a port 57 into which is threaded an L fitting 58 having a reducing coupling 59 for a line 60 leading from a compressor, or other source of supply of air under pressures indicated by a portion of the cylinder C; the line being provided with a hand valve 61 for manually controlling flow to the valve mechanism and with a lubricator 62 controlled by a valve 63 from which lubricant is supplied to the line by a press, indicated by hand wheel 64.

It is apparent that air admitted through the line 60 to the chamber 38 will force the valve 43 to its seat and retain it there to cut off flow to the well until the valve is opened by means presently described.

The valve housing member 31 of the secondary valve unit 29 includes a neck 65 that is threaded onto the cover plate 26 and a body portion enlarged to cooperate with a cover member 66 in forming a diaphragm chamber 67, the enlargement and cover member having flanges 68 connected by bolts 69, a diaphragm 70 being extended across the chamber 67 with its periphery located between the flanges 68 and clamped in place by the bolts 69.

Located in the neck 31 is a valve chamber 71 connecting with the diaphragm chamber 67 through a bore 72, the valve chamber having an upwardly facing seat 73 for a valve 74, having a stem 75 extended through the bore 72 into the diaphragm chamber 67, and there connected with the diaphragm 70 which is adapted for actuation within the chamber 67. A spring 76 seated on the diaphragm 70 of the chamber 67 about the stem 75 and retained in the recessed head 77 of an adjusting screw 78 threaded into the cover member 65 and secured on the housing by a lock nut 79, normally holds the diaphragm in down position to retain the valve 74 closed. The screw 78 serves as means for adjusting the tension of the spring so that operation of the diaphragm 70 for opening the valve 74 may be effected at any desired well pressure.

80 designates a conduit or valve supply line equipped with a filter 81, and leading from a point in the main supply line 60 between the valve 61 and valve chamber 38 and connecting with an opening 82 in the

neck 65 of housing 31 for communication with the valve chamber 71, and 83 designates a line leading from the chamber 71 to the top of the piston chamber 39.

The back pressure line 24, heretofore mentioned, leads from the bottom of the diaphragm chamber 66 to a point in the well considerably below the head level of the well, and is equipped with a hand valve 84, pressure indicator 85 and check valve 86 which prevents return flow of air pressure through the conduit from the chamber 66 to the well.

With the parts above mentioned constructed and assembled as described, and, assuming oil in the well to be below its head level (Fig. 1), as after preliminary swabbing or following a blowoff with the present apparatus, air admitted through the line 60 passes in major flow to the chamber 38 and forces the piston valve 43 to its seat, under which conditions no air is admitted to the well.

Oil flowing into the well from the sand rises into the trap past the check valve and within the well about the trap, finally submerging the outlet end of the pilot line 24 to liquid seal the line. When this sealing occurs, continued rise of oil in the well and pilot line causes the gas in the pilot line to be compressed until it builds up a pressure sufficient to lift the diaphragm 70 against tension of the spring 76 and unseat the valve 74. When the valve 74 is unseated, a minor flow of air passes from line 80 through the opening 82, valve chamber 71 and pipe 83, into the chamber 39 above the piston 44, building up a pressure in chamber 39 equal to the pressure in chamber 38, the first flow of air from pipe 83 closing the valve 99 (presently described) to prevent loss of air through the vent controlled by said valve. When this equalization of pressure occurs, the piston 44, being of greater area than the valve 43, is shifted downwardly to unseat the valve 43 and admit a major flow of air to the well through throat 42, nipple 54 and line 22; such flow acting to expel oil from the trap through tubing 8 and continuing until the trap is emptied and the major flow cut off, as I will now describe.

Mounted in the chamber 67' in the secondary valve housing 32 is a diaphragm 70', and connecting ports 87 and 88 leading from portions of the chamber 67' on opposite sides of the diaphragm is a pipe 89 provided with a downwardly seating check valve 90 for preventing return of air from the upper to the lower portions of chamber 67'. The lower portion of chamber 67' is in communication with the upper portion of the chamber 67 through a pipe 91 threaded into the ports 92 and 93 of the respective housing members 31 and 32.

Located in the housing 32 below the chamber 67' is a valve chamber 94 connect-

ed with the upper portion of the primary piston chamber 39 through a channel 95 and having a throat 96 above its seat 97 provided with a vent 98.

5 99 designates a valve located in chamber 94 and having a stem 100 extended through the throat 96 and through a bore 101 in the valve housing leading from the throat 96 into the chamber 67' where it is rigidly 10 connected with the diaphragm 70'. Weight 15 of the diaphragm 70' normally retains the valve 99 below its seat, so that air may be drained from the major flow chambers and lines through the vent port 98 when supply lines through the vent port 98 when supply 15 of major flow is cut off.

Leading from the nipple 54 in the major flow line to the port 87 in the housing 32 and communicating with the lower portion 20 of diaphragm chamber 67', is a branch 102 through which part of the major flow is diverted to chamber 67' below the diaphragm 70', and leading from the top of chamber 67' to storage tank 34 is a line 103 through which part of the air from the 25 major flow passing through the line 102, chamber 67' and pipe 89 is directed to the storage tank to build up a pressure therein equal to that of the major flow.

104 designates a return line from the tank 34 to the branch 102, including a back 30 check valve 105, for relief of the tank through the nipple 54, the master valve throat 42 and vent ports 106, which open from the piston valve chamber 39 directly 35 above the valve seat 41, into a manifold 107. A line 108 connects with the manifold for conducting the vented medium to a point of discharge.

When major flow to the well is established, as heretofore described, a part of the flow is diverted through the line 102 to the lower portion of chamber 67' lifting the diaphragm 70' to retain valve 99 and prevent escape of air from chamber 39. Air continuing to flow through line 102 opens the check valve 90 in the pipe 89 and passes to the upper part of the chamber 67' and through line 103 to the tank 34 to build up pressure in the tank equal to that of the major flow. Some of the air admitted to chamber 67' through the line 102 is delivered through pipe 91 into the top of chamber 67, depressing the diaphragm and closing valve 74, thereby cutting off minor flow 55 of air to the chamber 39, above the piston valve 44. Cutting off supply of air to chamber 39 by minor flow does not, however, affect the master valve, as a part of the major flow has passed through the channel in 60 the stem 45 to balance pressure in the chamber 39 and throat 42, so that the piston is held downwardly by gravity and due to the differential in area between the top of the piston and the lower face of valve 65 head 44'.

Air passing to the well trap in major flow under these conditions closes the check valve in the trap and lifts the oil, as heretofore mentioned. When the trap has been emptied, air from the major flow escapes through 70 the tubing, reducing pressure in the line 22 and in the lower portion of diaphragm chamber 67' below that in the tank 34, and back pressure from the tank through line 103 returns diaphragm 70' to its lower position, unseating valve 99 so that pressure on the piston 44 is relieved through channel 95 and vent 98, and the primary valve returned to initial position by pressure of the major flow on the piston valve 43, air 80 escaping from the upper portion of chamber 39 through the vent 98 more rapidly than it is admitted through the restricted terminal 52 of the channel 51 in stem 45, to unbalance the pressure and permit lift of the 85 piston.

The piston 44, when raised, exposes the vents 106, permitting air to escape therethrough from the chamber, and from the storage tank 34 into the manifold chamber 90 107, which encircles the valve housing member to pass off through the pipe 108.

The exhausting of the pressure continues until the parts again assume their original position, when major flow of air to the trap 95 is cut off, and the standing check valve is relieved and may open to permit the trap to be recharged with oil from the well, thereby lowering level of the oil relative to the pilot line, to uncover the line so that the apparatus may repeat its operation when the pilot line again becomes submerged by oil inflowing from the sand.

What I claim and desire to secure by Letters Patent is:

1. In combination with a well having a discharge line, a source of supply of fluid pressure medium having a supply line leading to the well, a return line leading from the well, and means controlling flow to the supply line by pressure in the return line including major valve and piston chambers, connected differential area valve and piston members in the respective chambers, the valve normally obstructing flow to the supply line, a minor flow line for conducting pressure medium to the piston chamber, and a valve operable by pressure in the return line to open the minor flow line and by pressure in the supply line to close the valve. 110

2. In combination with a well having a discharge line, a source of supply of fluid pressure medium having a supply line leading to the well, a return line leading from the well, and means controlling flow to the supply line by pressure in the return line including major valve and piston chambers, connected differential area valve and piston members in the respective chambers, the valve normally obstructing flow to the sup- 125

130

- ply line, a minor flow line for conducting pressure medium to the piston chamber, a diaphragm chamber, a diaphragm in said chamber, a valve for the minor flow line connected with said diaphragm, means urging the valve to closed position, the return line opening to said chamber at the side of the diaphragm to supply pressure for opening the valve, and means for supplying pressure medium from the supply line to the opposite side of the diaphragm for closing the minor flow valve.
3. In combination with a well having a discharge line, a source of supply of fluid pressure medium having a supply line leading to the well, a return line leading from the well, and means controlling flow to the supply line by pressure in the return line including major valve and piston chambers, connected differential area valve and piston members in the respective chambers, the valve normally obstructing flow to the supply line, a minor flow line for conducting pressure medium to the piston chamber, primary and secondary diaphragm chambers, diaphragms in said chambers, a valve controlling flow through the minor flow line and connected with the primary diaphragm, a spring urging said diaphragm to close said valve, the return line opening to the primary chamber at the side of the diaphragm opposite the spring to supply pressure for opening said valve against the tension of said spring, a vent from the major piston chamber, a valve controlling said vent and connected with the secondary diaphragm, means for conducting pressure medium from the supply line to the secondary diaphragm chamber to urge the secondary diaphragm to close the vent valve, means for conducting pressure medium so delivered to said secondary chamber to the primary diaphragm chamber to supplement tension of the spring in the primary diaphragm chamber for closing the valve in the minor flow line, a storage tank having back check connection with the supply line through the portion of the secondary diaphragm chamber opposite the connection with the primary chamber, for supplying the tank and for opening the vent valve by back pressure from the tank, and back check connection between the tank and supply line for equalizing pressure in the tank and line.
5. In combination with a well having a discharge line, a source of supply of fluid pressure medium having a supply line leading to the well, a primary valve normally closing the supply line, and responsive to fluid pressure for opening the line, a line for supplying fluid pressure medium to open the primary valve, a return line leading from the well, and means responsive to pressure induced by rising head of fluid in the return line controlling flow through the conducting line.
6. In combination with a well having a discharge line, a source of supply of fluid pressure medium having a supply line leading to the well, a primary valve normally closing the supply line, and responsive to fluid pressure for opening the line, a line for supplying fluid pressure medium to open the primary valve, a return line leading from the well, and means responsive to pressure induced by rising head of fluid in the return line for opening the conducting line and to greater pressure in the supply line for closing the conducting line.
7. In combination with a well having a discharge line, a source of supply of fluid pressure medium having a supply line leading to the well, a primary valve normally closing the supply line, and responsive to fluid pressure for opening the line, a line for supplying fluid pressure medium to open the primary valve, means controlling flow through the conducting line including a piston valve, and a return line leading from the well to the piston valve for opening the valve in response to pressure induced by rising head of fluid in the return line.
8. In combination with a well having a discharge line, a source of supply of fluid pressure medium having a supply line leading to the well, a primary valve normally

closing the supply line, and responsive to fluid pressure for opening the line, a line for supplying fluid pressure medium to open the primary valve, means controlling flow through the conducting line including a valve chamber in the conducting line, a piston chamber, connected piston and valve members in said chambers, a return line leading from the well to the unseating side of the piston chamber for unseating the valve in response to increase of pressure induced by rising head of fluid in the return line.

9. In combination with a well having a discharge line, a source of supply of fluid pressure medium having a supply line leading to the well, a primary valve normally closing the supply line, and responsive to

fluid pressure for opening the line, a line for supplying fluid pressure medium to open the primary valve, means controlling flow through the conducting line including a valve chamber in the conducting line, a piston chamber, connected piston and valve members in said chambers, a return line leading from the well to the unseating side of the piston chamber for unseating the valve in response to increase in pressure induced by rising head of fluid in the return line, and a line of communication between the supply line and opposite side of said piston chamber for reseating the valve in response to pressure in the supply line.

In testimony whereof I affix my signature.

GEORGE B. SMALL.
